[57] CLAIM

The ornamental design for a vehicle tire, as shown and described.

DESCRIPTION

FIG. 1 is a perspective view of a vehicle tire showing my new design it being understood that the tread pattern is repeated uniformly throughout the circumference thereof;

FIG. 2 is a front elevation view thereof; and,

FIG. 3 is a side elevation view thereof, the opposite side being a mirror image of that shown.

FIG. 1

FIG. 2

FIG. 3
